WILLIAM E. BIHL AND AXEL RAMCLAU, OF CHICAGO, ILLINOIS, ASSIGNEES TO IRON MOUNTAIN CO., OF CHICAGO, ILLINOIS, A CORPORATION OF ILLINOIS.

DISPENSING APPARATUS

Original application filed August 26, 1926, Serial No. 131,634. Divided and this application filed May 12, 1927. Serial No. 190,711.

The present invention relates to dispensing apparatus.

The present application is a division of application Serial No. 131,634, filed August 26, 1926, by the present applicants.

An object of the present invention is to provide means for storing and dispensing bottles of soft drink, milk or the like, which means is economical of space.

10 A further object is to provide combined cooling and dispensing apparatus for bottles which is efficient in its cooling operation and which is not likely to get out of order.

15 With these and various other objects in view, the invention may consist of certain novel features of construction and operation as will be more fully described and particularly pointed out in the specification, drawings and claims appended hereto.

20 In the drawings, which illustrate an embodiment of the device and wherein like reference characters are used to designate like parts—

Figure 1 is a view in front elevation of one 25 embodiment of the present invention;

Figure 2 is a sectional view taken along a vertical plane showing part of the interior of the construction shown in Figure 1;

Figure 3 is a sectional view taken along a 30 horizontal plane, indicated by the arrows 3—3 of Figure 1, showing part of the interior construction of the structure shown in Figure 1;

Figure 4 is a sectional view taken along a 35 plane indicated by the arrows 4—4 of Figure 3; and

Figures 5 and 6 illustrate details of construction.

Referring first to Figure 1, the numeral 10 40 indicates a casing, which may be made of sheet metal. Said casing may be provided with doors for permitting access to the interior thereof for inspection, repairs, and for the insertion of articles to be dispensed. One 45 of the doors referred to is indicated by the numeral 11 and is the door through which articles are charged into the apparatus.

The illustrated embodiment of the present invention constitutes means for refrigerating 50 and dispensing bottles, as for example bottles

containing soft drinks. The door 11 is therefore of a size and shape freely to admit soft drink bottles. Near the bottom of the casing 10 is a panel 12, which is removably secured to said casing 10 to permit access to the refrigerating means (not shown), which means may be a refrigerating machine.

Referring to Figure 3, it will be noted that the casing 10 is provided with heat insulating packing 13. A portion of one end wall 60 of said casing, indicated by the numeral 14, is removable, to permit ready access to the interior of said casing 10. Symmetrically disposed within the casing 10 is the brine tank 15, which brine tank contains cooling fluid. Surrounding the brine tank 15 is the ramp 16, which provides a sloping surface from a region near the top of the casing 10 to a lower region disposed at a level above the floor at which a person of ordinary height 70 may conveniently remove articles from said casing 10. Said ramp 16 may be described as having helical conformation, though it is intended in this specification that the term "helical" shall have a broader meaning than 75 its true mathematical meaning and shall include structures having an elliptical or other geometric shape in horizontal section.

Referring again to Figure 1, bottles may be inserted through the door 11 and placed 80 upon the ramp 16. The window 17 may be provided through which bottles within the casing 10 may be observed. As bottles pass down the ramp 16 they are discharged in succession through the outlet opening 18 onto 85 the base 19. The base 19 may be provided with a rack (not shown) for supporting the bottles as they are deposited from said base 19. Located at a convenient point is the bottle cap remover 20, which cap remover may 90 be of the ordinary conformation. Said cap remover 20 is preferably disposed directly above the base 19, whereby caps removed by said cap remover may drop through the rack 95 in the base 19 into the chute 21, whence they may drop into the drawer 22. Said drawer 22 may be opened at any time by an attendant, and the caps removed. The numeral 23 indicates a receptacle for straws, which re- 100

ceptacle may be positioned at a convenient height.

The present invention contemplates positive means for moving the bottles down the ramp 16, which positive means is responsive to coin controlled apparatus which will be described in detail hereinafter. The ramp 16, as illustrated, comprises the straps 24, which are shaped to provide a chuteway to hold bottles, indicated by the numeral 25, in a vertical position or in a position which is nearly vertical. Said ramp may be supported by any preferred supporting means. Said straps 24 are held in proper relation to one another by means of the holding means 26, which may be spaced at intervals along the ramp 16. The lowermost of said straps 24 is disposed symmetrically of the bottles carried thereby and offers very little friction to resist movement of said bottles. Also carried by the supporting members 26 are a plurality of pulleys disposed at intervals along the ramp 16, which pulleys form guiding means for a cable 27 to cause said cable to follow more or less generally the contour of the ramp 16. Said cable 27 is preferably an endless cable and has secured thereto the pusher 28. As indicated in Figures 3 and 5, the pusher 28 includes the member 29, having mounted thereon the roller bearings 30-30 adapted to have rolling engagement with one of the straps 24. Said member 29 is also provided with the upstanding member 31, adapted to engage the side of a bottle for pushing said bottle down the ramp 16. It will be understood that a line of bottles will be disposed upon the ramp 16, and that by pushing against the uppermost of said bottles the whole line will be pushed downwardly toward the discharge outlet 18. The cable 27 is adapted to be moved by the sheave 32, placed intermediate of the length of the endless cable 27. Said sheave 32 is adapted to be operated by the handle 33, which is connected through the shaft 34 to the clutch element 35, which clutch element is adapted to have clutching engagement with the clutch element 36. Said clutch element 36 is provided with the pinion 37 adapted to mesh with the gear 38, which gear 38 is rigidly connected to the sheave 32. After a person has deposited the necessary coin, he may, by turning the crank 33, connect the clutch elements 35 and 36, whereby by continuing to turn said crank 33 he will operate the sheave 32 to communicate motion to the endless cable 27 to cause movement of the pusher 28 and effect the discharge of a bottle from the outlet opening 18. Discharge of a bottle will automatically cause the disengagement of the clutch elements 35 and 36, whereby further rotation of the crank 33 will not effect the discharge of another bottle until another coin has been inserted.

66 The mechanism for performing the func-

tions immediately above referred to will now be described. Referring to Figures 3 and 4, the numeral 39 indicates a coin slot which coin slot is adapted to deliver the coin to the wheel 40. Said wheel 40 comprises a pair of spaced plates 41-41, which plates are spaced apart a sufficient distance to receive between them, flatwise, a coin such as is intended to operate the mechanism. Disposed in the periphery of a circle between said plates 41-41 are the pins 42-42, which pins 42 with the side plates 41 comprise a cage for the reception of the coin. The parts are so designed that the coin, which is indicated in Figure 4 by the numeral 43, projects radially a sufficient distance to engage the lever 44, which lever is pivoted upon the pin 45 and is spring-pressed in a counterclockwise direction by means which will be described presently. It will be obvious that as the handle 33 is turned to rotate the shaft 34 in a clockwise direction as the parts are viewed in Figure 4, the coin 43 will engage the upper extremity of the lever 44 to move said lever in a clockwise direction. Disposed to the left of the coin slot 39 as the parts are viewed in Figure 4 is the stop plate 44a adapted to abut the coin 43 if a person, after inserting a coin, should turn the shaft 34 in a counterclockwise direction. By reason of the provision of said stop plate 44a, the danger is averted that a person might, by turning the handle 33 in the wrong direction, have the coin drop out of operative position without operating the lever 44. Mounted near the lower extremity of the lever 44 is the stud 47 adapted to cooperate with the lever 48, which lever 48 is pivoted about the pin 49 and is urged in a counterclockwise direction by the spring 50, a stop 51 being provided for limiting the counterclockwise movement of the lever 48. When the lever 44 is moved in a clockwise direction by reason of the engagement therewith of the coin 43, the stud 47 carried by said lever 44 will be moved out of engagement with the adjacent extremity of the lever 48, permitting the spring 50 to move said lever 48 up against the stop 51, in which position the extremity of lever 48 will abut against the extremity of the stud 47, holding the lever 44 from returning to the position illustrated in Figure 4.

The numeral 52 indicates a bell crank lever pivotally mounted upon the pin 53. One arm of said bell crank lever 52 is resiliently connected to the lever 44 by means of the spring 54, said lever 44 being provided with a pin 54a extending through an aperture in the adjacent extremity of the bell crank lever 52; said spring 54 being disposed between said lever 54 and said adjacent end of the bell crank lever 52. Nuts 54b are disposed on the extremity of the pin 54a. The other arm of said bell crank lever 52 is provided with a yoke 55, by means of which rotation of the

bell crank lever 52 will communicate axial movement to the clutch element 35. The clutch elements 35 and 36 are urged apart by the coil spring 56, which coil spring, in a manner which will be obvious, insures the disengagement of said clutch elements 35 and 36, except when it is intended that they shall be engaged, and insures the smooth engagement of said clutch elements 35 and 36 in case 10 said clutch elements are presented in non-meshing relationship with one another.

The numeral 56 represents a star wheel having three vanes 57-57, which vanes are successively disposed in obstructing relationship to the bottles 25 upon the ramp 16. The numeral 58 indicates a stop for preventing the turning of the star wheel 56, except when said star wheel should be moved by engagement therewith of a bottle to be disposed from the machine. Said stop member 58 is illustrated in the form of a lever 59 pivoted upon the pin 60. One extremity of said lever 59 is adapted to be disposed in obstructing relationship to the star wheel 56. 25 The other extremity of said lever 59 is connected by means of rod 61 to the lever 44. When said lever 44 has been moved in a clockwise direction following the insertion of a coin, the rod 61 will be moved to the left as 30 the parts are viewed in Figure 4, whereby the upper extremity of the lever 59 will be disposed out of obstructing relationship with the star wheel 56.

As each bottle 25 is moved in succession to 35 the lower extremity of the ramp 16, it is adapted to drop upon a trap door 62. Said trap door 62 is provided with the crank 63, which crank is connected to the lever 48 by means of the link 64. The dropping of the 40 trap door 63 will cause a downward movement of the link 64, resulting in clockwise movement of the lever 48 in opposition to the spring 50. This movement will disengage the left-hand extremity of the lever 48 45 from stud 47 (Figure 4), whereby the lever 44 may move into the position shown in Figure 4, thereby completing the cycle of operation.

When the attendant of the illustrated dispensing apparatus desires to charge bottles into said apparatus, he may, by inserting a coin, connect the clutch elements 35 and 36 in the manner above referred to by turning the shaft 34 in a clockwise direction; thereafter, 50 by turning handle 33 in a direction to move the shaft 34 in a counterclockwise direction, he may move the pusher 28 up to the upper region of the ramp 16. He may then charge bottles into said dispensing apparatus one 55 after another.

Attention is now directed to the structure illustrated in Figure 6. Before charging bottles into the apparatus, the attendant should, of course, move the pusher 28 to its 60 uppermost position to the right of the door

11 as the parts are viewed in Figure 1; otherwise the bottles charged into the apparatus will be in rear of said pusher 28 and will not be pushed downwardly by said pusher when said pusher is moved downwardly by the coin controlled mechanism. Accordingly, the present invention contemplates the provision of a shutter 65, spring-pressed to closed position across the opening controlled by the doorway 11. Said shutter is provided with a finger 66 adapted to be engaged by the member 31 or other part of the pusher 28. When said pusher 28 is moved to the upper limit of its travel, said pusher will, by reason of its engagement with the finger 66, positively move the shutter 65 into the diagonal or guiding position indicated in dotted lines in Figure 6, in which the swinging edge of said shutter abuts against the inner strap 24. Said shutter 65 is curved about a vertical axis, and when said shutter is in guiding position it serves as guide means for directing the bottles in the proper direction onto the ramp 16. When said shutter 65 is in closed position, as indicated in full lines in Figure 6, it will indicate to the attendant that the pusher 28 is not in its uppermost position and that said pusher should be moved to said uppermost position before bottles are charged into the apparatus. If desired, a suitable warning may be placed upon said shutter 65.

After having charged the apparatus, the attendant will then turn the handle 33 in a direction to move the shaft 34 in a clockwise direction as the parts are viewed in Figure 4. Inasmuch as the shutter 65 is spring-pressed to closed position, it will close automatically when the pusher 28 is moved downwardly. Inasmuch as the clutch elements 35 and 36 are in engagement, motion will be communicated from said handle through clutch elements 35 and 36 to pinion 37 and gear 38 to turn the sheave 32. This action will move the cable 27, whereby the pusher 28 will move the line of bottles downwardly. At this time the lever 44 will be held in its clockwise position, whereby the rod 61 will hold the lever 59 out of obstructing relationship with the star wheel 56. Movement of the pusher 29 will therefore result in the moving of the bottle 25 to the trap door 62, whence said bottle will drop through the outlet opening 18 onto the base 19, from which said bottle may be removed. As noted above, movement of the trap door 62 will cause the crank 63 to move the link 64 downwardly, moving the lever 48 in a clockwise direction, allowing the lever 44 to move to the position indicated in Figure 4. Such movement of the lever 44 will cause the clockwise movement of the bell crank lever 52, resulting in disengagement of clutch elements 35 and 36. The operator may then 120 insert the bottle which he has discharged back 125

65 130

into the machine through the door 11 for storage purposes and may lock said door 11.

When any person desiring to secure a bottle inserts a coin within the slot 39 and communicates a turning movement to the handle 33 in a direction to move the shaft 34 in a clockwise direction, the coin, indicated by the numeral 43 in Figure 4, will cause the lever 44 to swing in a clockwise direction, resulting in the engagement of the clutch elements 35 and 36 as above described, whereby turning of the handle 33 will push the bottle onto the trap door 62, from which said bottle will drop through the outlet opening 18 onto the base 19 in a manner described above. As also described above, the operation of the trap door, by reason of its connection with the lever 48, will interrupt the driving connection between the clutch elements 35 and 36.

After each coin 43 has passed the upper extremity of the lever 44 it will drop out into a convenient coin receptacle, such a receptacle being indicated in Figure 1 by the numeral 67.

Though a handle 33 has been illustrated for operating the mechanism for moving the pusher 28, it will be clear that any other preferred motive means may be used if preferred. It should be noted, further, that the refrigerating and dispensing apparatus embodying the principles of the present invention permits dry, regulated refrigeration, delivering dry bottles.

It has been found in practice that ordinary soft drink bottles will slide with sufficient ease on the ramp 16, particularly with the speed reduction gears 37 and 38, so that no antifriction bearings are required for said bottles. Any such bearings may be used, of course, if preferred.

Though a preferred embodiment of the present invention has been described in detail, many modifications will occur to those skilled in the art. It is intended to cover all such modifications that fall within the scope of the appended claims.

What is claimed is—

1. In dispensing apparatus, a casing, a ramp for carrying articles to be dispensed, said casing being provided with an inlet opening for said articles and an outlet opening for said articles, a pusher for pushing said articles down said ramp, and a combined shutter and article guiding member responsive to the position of said pusher for guarding said inlet opening except when said pusher is in position to cooperate upon articles disposed adjacent to said inlet opening.

2. In dispensing apparatus, a casing, a ramp for carrying articles to be dispensed, said casing being provided with an inlet opening for said articles and an outlet opening for said articles, a pusher for pushing said articles down said ramp, and a combined shutter and article guiding member responsive to the position of said pusher for guarding said inlet opening except when said pusher is in position to cooperate upon articles disposed adjacent to said inlet opening.

70 sive to the position of said pusher for guarding said inlet opening except when said pusher is in position to cooperate upon articles disposed adjacent to said inlet opening, said combined shutter and guiding member being biased to guiding position.

3. In cooling and dispensing apparatus, in combination, a casing, a ramp for carrying articles to be dispensed, said casing being provided with an inlet opening for said articles and an outlet opening for said articles, a combined shutter and article guiding member for normally closing said inlet, a pusher member movable along the ramp toward the discharge opening for discharging the articles therethrough, and cooperating means carried by the pusher member and the shutter member for opening the latter when said pusher member is moved into position at the side of the inlet opening more remote from the outlet opening.

4. In a device of the character described, the combination of a ramp, inlet and outlet means for said ramp, means whereby articles to be dispensed are discharged from said ramp, a member associated with said ramp for operating said last named means, said member having means for operating said inlet means to open position whereby ingress is had to said ramp, to charge said ramp with articles to be dispensed.

5. In a device of the character described, the combination of a substantially helically disposed ramp, a track associated with said ramp, means on said track operable to move articles along said ramp, an endless operating member operable to move said means, inlet and outlet means for said ramp, means whereby articles to be dispensed are discharged from said ramp, said first named means having means for operating said inlet means to open position whereby ingress is had to said ramp to charge said ramp with articles to be dispensed.

Signed at Chicago, Illinois, this 7th day of May, 1927.
